UNITED STATES PATENT OFFICE.

FREDERICK CONRAD STOBER AND HENRY ADAM STOBER, OF SACRAMENTO,
CALIFORNIA.

CHIMNEY AND VENTILATOR CAP.

SPECIFICATION forming part of Letters Patent No. 535,634, dated March 12, 1895.

Application filed September 4, 1894. Serial No. 522,142. (No model.)

To all whom it may concern:

Be it known that we, FREDERICK CONRAD STOBER and HENRY ADAM STOBER, citizens of the United States, residing at Sacramento, in 5 the county of Sacramento and State of California, have invented certain new and useful Improvements in Chimney and Ventilator Caps, of which the following is a full, clear, and exact description, reference being had to 10 the accompanying drawings, forming part of this specification, in which—

Figure 1, is a perspective view of a chimney and ventilator embodying our invention. Fig. 2, is a top plan view of the same.

15 In the said drawings A represents the upper portion and B the lower portion of a chimney top which converges from its upper end downwardly as shown. Intermediate of the ends of this chimney top are placed four 20 tubes or pipes C, D, E and F having flanges at their bases by which they are bolted to the chimney top, with their inner ends or bases of larger diameter than the lower or outer ends whereby said pipes or tubes converge 25 from their bases downwardly and outwardly. Over the top of the chimney is placed a cap G whose diameter is in excess of that of the larger end of the chimney A—B which cap may be of any ornamental nature, and is sup- 30 ported rigidly above the top of the chimney A—B by means of four arms H, I, J and K which are inclined inwardly toward the said chimney A—B and thence extend downwardly along the exterior of the same, and 35 have their lower ends turned outwardly and upwardly to form hooks, adapted to furnish means for the attachment of rods or guys whereby the device is anchored securely in

position. These arms, therefore, not only support the large cap in place above the chimney A—B, but they also furnish a simple means by which rods or guys may be used as an anchor or means for steadyng and securely fixing the whole device in its proper position. The purpose of converging the 45 tubes C, D, E and F downwardly is, first, to create an upward draft from winds which strike the chimney sidewise, and, second, to allow the escape of air which may beat downward from the top, without checking the draft 50 and forcing the smoke back into the room.

We are aware that chimney tops have been made diverging from the top downwardly, and have pipes or tubes entering the same at points between their ends, and such construc- 55 tion we do not broadly claim; but

What we do claim, and desire to secure by Letters Patent, is—

An improved chimney and ventilator cap consisting of a chimney or body portion con- 60 verging from its upper end downwardly, pipes or tubes entering the same between its ends and converging from their bases downwardly and outwardly, a cap of large diameter above the top of the chimney or body portion and 65 arms depending from the cap extending down along the exterior of the chimney or body, and secured thereto, and having their lower ends formed into hooks adapted to receive rods or guys for anchoring the device in po- 70 sition, as herein described.

FREDERICK CONRAD STOBER.
